ILLUMINATOR FOR MICROSCOPES

Willard T. Perkins, Irondequoit, N. Y., assignor
to Bausch & Lomb Optical Company, Rochester, N. Y., a corporation of New York

Application January 26, 1951, Serial No. 13,980

Term of patent 14 years

(Cl. D57—1)

To all whom it may concern:

Be it known that I, Willard T. Perkins, a citizen of the United States and a resident of the town of Irondequoit, county of Monroe, and State of New York, have invented a new, original, and ornamental Design for an Illuminator for Microscopes, of which the following is a specification, reference being had to the accompanying drawing, forming a part hereof.

Fig. 1 is a front view of an illuminator for microscopes showing my new design.

Fig. 2 is a perspective view of same showing the top, rear and a side.

Fig. 3 is a perspective view showing the bottom and opposite side shown in Fig. 2.

The broken line showing of a part of a microscope in Fig. 3 is for illustrative purposes only.

I claim:

The ornamental design for an illuminator for microscopes, substantially as shown and described.

WILLIAM T. PERKINS.
